UNITED STATES PATENT OFFICE.

JOHN GOOD, OF BROOKLYN, NEW YORK, ASSIGNOR TO GOOD INVENTIONS CO., OF NEW YORK, N. Y., A CORPORATION OF NEW YORK.

INTERNAL-COMBUSTION-ENGINE SYSTEM.

Application filed April 6, 1915, Serial No. 19,610. Renewed June 11, 1920. Serial No. 388,348.

To all whom it may concern:

This specification is to bear witness that I, JOHN GOOD, a citizen of the United States, residing in Brooklyn, New York, have invented the following-described Improvements in Internal-Combustion-Engine Systems.

The invention relates to the use of carburettor-type engines having small clearances and therefore high compression pressures, and its direct object is to prevent the admission of excessive fuel charges to such engines as will later appear. The invention is illustrated in connection with a vacuum cleaning system in which the engine is used as a source of suction according to principles already well known. As so used it eliminates the pump mechanism ordinarily employed in such systems and also affords incidental advantages and economies as will hereinafter appear. In the drawings forming part of this specification,

Fig. 1 represents an engine operating a vacuum system in accordance with the invention, parts being in section;

Fig. 2 a modification thereof.

The engine shown is a common type of four-cycle combustion engine with a suction operated carburetor or charge-forming apparatus, and having a very small clearance. The intake pipe is connected to the carburetor 2 in the usual way and the latter is illustrated in the present case as entirely enclosed, except for the adjustment screws and drain cock, in a casing or box 3 to which box air has entrance only through the vacuum pipe 4. The carburetor 2 may be of any usual or suitable type and in the present case may be understood as comprising a float controlled liquid chamber 5 supplied with liquid from a tank 6, and a fuel nozzle 7 leading from the liquid in the chamber to the mixing space 8 which space forms a continuation of the intake pipe 1 as usual. An air check valve 9 loaded with an adjustable spring controls the passage of the air from the casing 3 into the intake and the cover of the liquid chamber is provided with a vent hole 10 by which the pressure of the air in the casing is transmitted to the liquid chamber, the pressure in said chamber being at all times the same as in the casing 3 outside of the carburetor. The set screws 11 and 12 control respectively the tension of the spring on the air check 9 and the ca-

pacity of flow through the fuel nozzle 12. The vacuum pipe 4 is equipped with an automatic throttle 13 under the control of a flexible diaphragm 14 so combined with a spring and set screw that when the vacuum in the pipe at the service side of the throttle increases for any reason, the throttle is automatically moved in the direction to open it, and vice-versa, thus tending to maintain a substantially constant condition of relative vacuum on the engine side of the throttle, but particularly this throttle serves to safeguard the engine against taking in an excessive charge of combustible mixture which, on account of the small clearance of the engine might cause the resulting pressure in the cylinder to exceed the safety limit of the cylinder casting. The automatic throttle control is thus to be understood as a precautionary safeguard against accidents and as a means of maintaining constant working conditions.

The outer end of the vacuum pipe 4 is connected, in the case in hand, to a filter chamber 15 containing the usual removable cloth filter bag or bags 16, and the operating hose or vacuum service pipe 17 is connected to the chamber on the opposite side of the bag. An air vent valve 18 is also connected to the filter chamber, preferably on the same side as the service hose, the spring thereof being adjustable and set to admit air to the vacuum pipe when the air passage through the service hose 17 has reached some predetermined limit of obstruction.

In the operation of the apparatus, the vacuum produced by the suction strokes of the engine piston is of a relatively high degree between the engine and the air check 9 due, of course, to the spring load on the latter, and it is relatively of low degree between the said air check and the throttle or air filter due to the presence of the restriction represented by the throttle or by the work being done by the service hose. This relatively lower vacuum in the service pipe, however, is of sufficient value to serve adequately the purposes indicated and various degrees of vacuum can be produced and maintained according to the design of the engine and the adjustment of the vent valve 18. This lower degree of vacuum being present in the liquid chamber of the carburetor as well as at the entrance past the air check

9, will cause the liquid fuel of the tank 6 to flow upwardly into the liquid chamber, if the said tank is at a lower level, and the flow of the liquid through the fuel nozzle 7 will 5 take place according to the difference of the pressure in the liquid chamber and in the mixing space 8, the operation being in no respect different from the carburetor if exposed to atmosphere. Excessive inflow of 10 fuel from the tank 6, due to the relative vacuum in the casing 3, is prevented by the float operated valve 19 quite the same as if the fuel were supplied by gravity or by a forced feed system and a constant level 15 is thereby maintained in the liquid chamber, so that the discharge of the liquid fuel through the nozzle 7 is proportional to the air supply or at least as true to constant proportion as if the carburetor were exposed 20 to atmosphere in the usual way.

It will be evident that the automatic throttle prevents the admission of dangerously excessive charges to the engine as above stated, because for example, as the cleaning 25 tool 20 is raised from the floor and its throttling action on the engine thereby almost entirely removed (substantially corresponding to wide opening of the throttle in a manually controlled engine) the relief of the 30 vacuum on the underside of diaphragm 14 causes the automatic throttle to move immediately toward closing and by proper setting of the spring of throttle 13 it will be apparent that the action may be regulated as 35 desired.

The air chamber 3 which serves as a vestibule to the mixing space of the carburetor may be reduced in size so as in fact to be no 40 larger in diameter than the mixing space itself provided only that the pressure therein be transmitted to the liquid chamber of the carburetor but the larger size, as shown in the drawings, is preferable inasmuch as it serves the effect of an airdome to smooth 45 down the pulsations of the reciprocating piston especially in the case where the engine is single cylinder. The air filter also serves the same purpose.

In Fig. 2 the modification illustrated 50 consists merely in enclosing the crank case of the engine and subjecting the interior thereof and the reverse end of the piston to the same relative vacuum which obtains in the casing 3. This is done by connecting the said crank 55 case into the vacuum pipe between the throttle 13 and the casing so that all the air entering the latter will pass through the crank case. Thereby the difference of pressure on the opposite ends of the piston, when 60 making its suction stroke, is considerably less than if the said crank case space were exposed to atmosphere and, although the difference is correspondingly greater when the piston is making its compression stroke, the 65 general operation is improved and ill-smell-

ing gases and vapors normally issuing from the crank case are carried away which is an advantage where the apparatus is installed in dwellings. In both forms described above, the danger from excessive fuel charges is 70 prevented by the automatic throttle and further eliminated by the safety valve 23, connected with the combustion chamber, which is set to blow off at some pressure well within the safety limit. 75

I claim:

1. A vacuum system comprising an internal combustion engine having a suction operated carburetor, a vacuum pipe connected to the intake of said carburetor, means for preventing disturbance in the operation of the carburetor by variation of the vacuum in said vacuum pipe and an automatic vacuum-operated throttle in said vacuum pipe. 80

2. A vacuum system comprising an internal combustion engine having small piston clearance and a suction operated carburetor, a casing enclosing the air intake thereof, a vacuum pipe connected to said casing, means whereby the vacuum condition in said casing is transmitted to the liquid chamber of the carburetor and means in said vacuum pipe for preventing the admission of dangerous charges to the engine. 90

3. A vacuum system comprising an internal combustion engine having small piston clearance and a suction intake, a vacuum pipe connected with said intake, a suction nozzle connected to said pipe, and means for subjecting the crank shaft end of the engine piston to the relative vacuum in said vacuum pipe. 100

4. The combination of an internal combustion engine having relatively small piston clearance, an intake passage leading thereto, a suction operated carburetor, and means operating by change of the relative vacuum in said intake for automatically preventing admission of excessive mixture 105 charge to the engine. 110

5. The combination with an internal combustion engine having a variable and manually controlled inlet restriction, of an automatic throttle and means sensitive to the intake vacuum to close the automatic throttle when the vacuum falls through the variation of said restriction, to prevent the admission of dangerously excessive charges to the engine. 115

6. The combination with an internal combustion engine having manually operable inlet restriction means, of an automatic throttle and means sensitive to the intake vacuum between said manual means and the 120 automatic throttle to close the automatic throttle when the vacuum falls, to prevent the admission of dangerously excessive charges to the engine. 125

7. In an internal combustion engine, the 130

- combination of an engine cylinder, a carburetor having spray means and mixing space and having its mixture outlet connected to said engine cylinder, a fuel supply tank for being also subject to said partial vacuum and variably controlled throttle means 25 adapted for controlling the flow through said intake passage.
5. said spray means, a closed engine crank case, an air passage connecting said crank case to the inlet of the carburetor and an entrance for atmospheric air to the crank case, said air entrance constituting the main air 10 entrance for combustion supporting air and being restricted and thereby adapted to maintain a condition of partial vacuum in said crank case and mixing space capable of lifting liquid fuel from said tank at a 15 lower level to the spray means of the carburetor.
8. An internal combustion engine having a closed crank case and a suction intake passage including a carburetor, a float-controlled liquid fuel receptacle for said carburetor, said closed crank case being subject 20 to the partial vacuum existing in said intake passage and said float-controlled receptacle
9. In an internal combustion engine, an intake passage including carburetting means and also including the engine crank-case, in combination with a fuel supply tank at a level below said carburetting means, said crank-case having an air entrance and the restriction to flow through said entrance serving to establish a vacuum effect on said carburetting means suitable for lifting fuel thereto from said supply tank at the lower level. 30 35
- In testimony whereof, I have signed this specification in the presence of two witnesses.
